CONVERSION OF HYDROCARBON OILS

Charles H. Angell, Chicago, Ill., assignor to Universal Oil Products Company, Chicago, Ill., a corporation of Delaware

Application August 5, 1935, Serial No. 34,655

5 Claims. (Cl. 196—49)

This invention particularly refers to an improved process for the conversion of hydrocarbon oils accompanied by continuous coking of the residual liquid conversion products wherein charging stock for the process, comprising hydrocarbon oil of relatively high-boiling characteristics or an oil containing a substantial proportion of high-boiling materials, is subjected to vaporization by being commingled with hot vaporous products from the coking stage of the process and the resulting non-vaporous high-boiling components of the charging stock either subjected to coking together with said residual liquid conversion products or subjected to relatively mild conversion in a reaction chamber of the cracking system preceding the coking stage by contact therein with highly heated products from the cracking coil of the system.

One of the most satisfactory methods which 20 has been developed for the continuous coking of relatively heavy oils, such as high-boiling residual oils resulting from pyrolytic conversion, comprises passing the oil through a heating coil wherein it is quickly heated to a high conversion 25 temperature under non-coking conditions and introducing the highly heated oil into an enlarged coking zone, preferably operated at substantially atmospheric or relatively low superatmospheric pressure, wherein its reduction to substantially 30 dry coke is accomplished.

In such methods of operation there is a large amount of available heat in the vaporous products evolved during the coking operation due to the relatively high temperature to which the 35 heavy oils subjected to coking are heated and, in accordance with the usual practice, a large proportion of this available heat is wasted. Also due to the high temperature and relatively low pressure employed in the coking operation the 40 vaporous products from the coking zone normally contain a considerable amount of high-boiling materials, including entrained or dissolved tars and pitch-like material, unsuitable for conversion in the heating coil of the system to which the 45 normal reflux condensate is supplied.

In the present invention a large portion of the available heat in the vaporous products from the coking zone is utilized to effect substantial vaporization of the hydrocarbon oil charging 50 stock for the process by directly commingling the hot vaporous products from the coking zone with the charging stock in a vaporizing zone succeeding the coking chamber. The partial cooling of the vaporous products from the coking zone thus 55 effected by their contact with the relatively cool

charging stock serves to remove the undesirable high-boiling materials from the vaporous products, allowing only relatively clean vapors to pass from the vaporizing chamber to the fractionating zone of the system wherein the normal reflux condensate which is supplied to the heating coil of the cracking system is recovered. The undesirable high-boiling materials removed from the vaporous products of the coking operation by contact with the charging stock in the vaporizing 10 chamber commingle with the high-boiling components of the charging stock remaining unvaporized in this zone and, in accordance with the process of the present invention, these commingled relatively high-boiling materials may be 15 supplied either to the heating coil of the coking stage or are directed without additional heating to the same high-pressure reaction chamber of the cracking system to which the highly heated products from the heating coil of the cracking 20 stage are supplied.

It will be understood, of course, that the two alternative methods of operation with respect to the disposition of the commingled high-boiling oils from the vaporizing chamber are not to be 25 considered equivalent but may be selected, depending primarily upon the characteristics of the commingled oils, to give the best results with respect to yield of the desired products, continuity 30 of operation, throughput, etc.

In one embodiment, the invention comprises subjecting hydrocarbon oil, comprising insufficiently converted intermediate liquid products of the process, to conversion conditions of cracking temperature and substantial superatmospheric pressure in a heating coil and communicating reaction chamber, withdrawing both vaporous and liquid conversion products from the reaction chamber and introducing the same into a reduced pressure vaporizing chamber wherein 40 separation of vapors and residual liquid conversion products is accomplished, withdrawing non-vaporous residual liquid from the vaporizing chamber, heating the same to a high conversion 45 temperature under non-cracking conditions in a separate heating coil, introducing the highly heated residual oil into a coking zone wherein its reduction to substantially dry coke is accomplished introducing vaporous products withdrawn from the coking zone and vaporous products from the vaporizing chamber into a separate vaporizing chamber, introducing hydrocarbon oil charging stock for the process into said separate vaporizing chamber in contact with the vaporous products supplied thereto, subjecting the result- 50 55

ing vaporous products from said separate vaporizing chamber to fractionation, returning the resulting reflux condensate to the first mentioned heating coil, subjecting fractionated vapors 5 of the desired end-boiling point to condensation, collecting and separating the resulting distillate and gas, withdrawing from said separate vaporizing chamber high-boiling components of the charging stock which remain unvaporized in this 10 zone, together with high-boiling materials removed from the vaporous products supplied thereto, and introducing the same into the reaction chamber wherein they are subjected to relatively mild conversion by contact in this zone 15 with the highly heated products from the first mentioned heating coil.

As an alternative to the specific embodiment of the process above described the high-boiling oils from said separate vaporizing chamber may 20 be supplied to the heating coil of the coking stage of the system, together with the non-vaporous residual liquid products from the first mentioned vaporizing chamber, being thereby heated to a high temperature under non-coking conditions 25 and subjected to coking in the succeeding coking zone.

The accompanying diagrammatic drawing illustrates one specific form of apparatus embodying the features of the present invention and in 30 which the process of the invention may be accomplished.

Referring to the drawing, heating coil 4 is located within a furnace 2 of any suitable form by means of which the oil supplied to this zone, in 35 the manner to be later more fully described, is heated to the desired conversion temperature preferably at a substantial superatmospheric pressure and the resulting highly heated products are directed from the heating coil through line 3 40 and valve 4 into reaction chamber 5.

Reaction chamber 5 is also preferably maintained at a substantial superatmospheric pressure and this zone is preferably well insulated, although insulation is not shown in the drawing, 45 in order to prevent the excessive loss of heat by radiation so that conversion of the heated products, and particularly their vaporous components, may continue in this zone. In the case here illustrated both vaporous and liquid conversion 50 products are withdrawn in commingled state from the lower portion of chamber 5 and are directed through line 6 and valve 7 into vaporizing and separating chamber 8. It is, of course, also within the scope of the present invention to 55 separately withdraw vaporous and liquid conversion products from the reaction chamber in which case the vaporous products separately withdrawn from this zone at any desired point or plurality of points therein may be separately supplied, by well 60 known means, not illustrated, to vaporizing chamber 8 at any desired point or plurality of points in this zone or they may be directed, all or in part, to vaporizing chamber 26 or to fractionator 34 or, when desired, to coking chamber 21 by well known means, not shown.

Vaporizing chamber 8 is preferably maintained at a substantially reduced pressure relative to that employed in reaction chamber 5 by means of which appreciable further vaporization of the liquid conversion products supplied to this zone from the reaction chamber is accomplished. Separation of vapors and non-vaporous residual liquid is 70 accomplished in chamber 8, the vapors being withdrawn from the upper portion of this zone through line 9 and valve 10, and they may be 75

supplied through line 11, all or in part, to vaporizing chamber 26 or they may be supplied, all or in part, by well known means, not illustrated, to fractionator 34. Residual liquid conversion products remaining unvaporized in chamber 8 are withdrawn from the lower portion of this zone through line 12 and valve 13 to pump 14 by means of which they are fed through line 15, valve 16 and line 54 to heating coil 17.

Heating coil 17 is located within a furnace 18 and this heating coil and furnace are preferably of such design, which is now well known, that the relatively heavy oil supplied thereto, which is preferably passed through the heating coil at a relatively high velocity, is quickly heated to a high conversion temperature without allowing it to remain in the heating coil and communicating lines for a sufficient length of time to permit any excessive formation and deposition of coke in this zone. The highly heated residual oil is directed 20 from heating coil 17 through line 19 and valve 20 into coking chamber 21 wherein it is reduced to substantially dry coke by virtue of its highly heated condition.

The coke produced in chamber 21 may be allowed to accumulate in this zone to be removed therefrom in any suitable well known manner, not illustrated, after the operation of the chamber is completed. Although, for the sake of simplicity, only one coking chamber is shown in the drawing two or more such zones are preferably employed and may be operated simultaneously or, preferably, are alternately operated, cleaned and prepared for further operation in order that the coking stage, in common with the rest of the system, may be operated continuously. Chamber 21 is provided with a suitable drain-line 22 controlled by valve 23 which may also serve as a means of introducing steam, water or any other suitable cooling material into the chamber after its operation is completed and after it has been isolated from the rest of the system in order to hasten cooling of the chamber and facilitate the removal of coke therefrom. Vaporous products evolved in chamber 21 are withdrawn from the upper portion of this zone through line 24 and valve 25 and are directed through line 11 to vaporizing and separating chamber 26.

Hydrocarbon oil charging stock for the process, which may comprise any desired type of oil but is preferably either an oil of relatively wide boiling range, such as crude petroleum, topped crude, or the like, or an oil of high boiling characteristics, is supplied through line 27 and valve 28 to pump 29 by means of which it is fed through line 30 and valve 31 into vaporizing chamber 26 wherein it is intimately contacted with the hot vaporous products from the coking zone, as well as, when desired, from vaporizing chamber 8 and/or reaction chamber 5, and thereby subjected to appreciable vaporization. It will be understood, of course, that the charging stock may, when desired, be preheated to any desired temperature below that of the vaporous products with which it is contacted in chamber 26, prior to its introduction into this zone although, for the sake of simplicity, none of the well known means for accomplishing this are illustrated in the drawing. Cooling of the hot vaporous products supplied to chambers 26 by contact with the charging stock in this zone serves to remove therefrom undesirable high-boiling components including any tarry or pitch-like material dissolved or entrained in the vaporous products from the coking zone. Accurate control of the degree of vaporization

zation to which the charging stock is subjected in chamber 26 and the characteristics of the high-boiling components of the charging stock and vaporous products recovered as liquid from chamber 26 may be obtained by controlling the quantity and temperature of the charging stock supplied to the vaporizing chamber and the pressure conditions maintained in this zone. The relatively low-boiling components of the charging stock which are vaporized in chamber 26 and the components of the vaporous products supplied to this zone which remain uncondensed therein are directed through line 32 and valve 33 to fractionation in fractionator 34.

15 The components of the vaporous products supplied to fractionator 34 boiling above the end-boiling point of the desired final light distillate product of the process are condensed in this zone as reflux condensate which is withdrawn from the lower portion of the fractionator through line 35 and valve 36 to pump 37 by means of which it is supplied through line 38 and valve 39 to conversion in heating coil 1, in the manner previously described. Fractionated vapors of the desired end-boiling point are withdrawn, together with uncondensable gas produced by the process, from the upper portion of the fractionator through line 40 and valve 41 and are subjected to condensation and cooling in condenser 42.

20 The resulting distillate and gas passes through line 43 and valve 44 to collection and separation in receiver 45. Uncondensable gas may be released from the receiver through line 46 and valve 47. Distillate may be withdrawn from receiver 45 through line 48 and valve 49 to storage or to any desired further treatment. A regulated portion of the distillate collected in receiver 45 may, when desired, be recirculated by well known means, not illustrated, to the upper portion of fractionator 34 to serve as a cooling and refluxing medium for assisting the fractionation of the vapors and to maintain the desired vapor outlet temperature from the fractionator.

25 High-boiling components of the charging stock remaining unvaporized in chamber 26 commingle in this zone with the high-boiling components of the vapors removed therefrom by contact with the charging stock and the commingled materials are removed from the lower portion of chamber 26 through line 50 and valve 51 to pump 52 by means of which they are fed through line 53 and may be directed through valve 54 and line 55 into heating coil 17, to be subjected to heating in this zone together with the residual liquid conversion products from chamber 8 and subjected to subsequent reduction to coke in coking chamber 21, or, as an alternative method of operation, all or a regulated portion of the commingled high-boiling oils from chamber 26

30 may be directed through valve 56 in line 53 into reaction chamber 5 preferably being sprayed against the walls of the chamber by means of a suitable spreader flange or spray arrangement such as indicated, for example, at 57. By the latter method of operation the high-boiling oils from chamber 26 are subjected to relatively mild conversion in chamber 5 by contact with the highly heated products from heating coil 1, the resulting vaporous and liquid conversion products

35 commingling with the vaporous and liquid products resulting from conversion of the lower boiling oils supplied to heating coil 1 and being subjected, in the portions of the cracking system subsequent to chamber 5, to the same conditions of further treatment previously described.

In a process of the character illustrated and above described the preferred range of operating conditions may be approximately as follows: The heating coil of the cracking stage of the system to which reflux condensate from the fractionator is supplied may utilize an outlet conversion temperature ranging, for example, from 850 to 1000° F., preferably with a superatmospheric pressure measured at the outlet from the heating coil of from 100 to 800 pounds, or thereabouts, per square inch. A substantial superatmospheric pressure, which may be substantially the same or somewhat lower than the pressure employed in the heating coil, may be utilized in the succeeding reaction chamber and the vaporizing chamber to which the liquid conversion products or both liquid and vaporous conversion products from the reaction chamber are supplied preferably employs a substantially reduced pressure relative to that in the reaction chamber which may range, for example, from 150 pounds, or thereabouts, per square inch down to substantially atmospheric pressure. The temperature employed at the outlet from the heating coil of the coking stage of the system may range, for example, from 900 to 1050° F. preferably with a superatmospheric pressure in this zone of from 20 to 150 pounds, or thereabouts, per square inch, although lower or higher pressures may be employed, when desired. The coking chamber may be operated at any desired pressure ranging from 150 pounds, or thereabouts, per square inch down to substantially atmospheric pressure, which pressure, however, is no greater than that employed in the preceding heating coil. The vaporizing and separating chamber succeeding the coking chamber, to which charging stock for the process is supplied, may utilize any desired pressure from substantially atmospheric to 150 pounds, or thereabouts, per square inch superatmospheric pressure which, however, is no greater than the pressure employed in the coking chamber. The pressures employed in the fractionating, condensing and collecting portions of the system may be substantially the same or somewhat lower than the pressure employed in the last mentioned vaporizing and separating chamber.

As a specific example of one of the many possible operations of the process as it may be accomplished in an apparatus of the character illustrated and above described, the charging stock, which comprises an 18° A. P. I. gravity Mid-Continent reduced crude, is supplied to a vaporizing chamber to which vaporous products from the coking zone of the system are also supplied and contacted with the charging stock, vaporous products from this zone are supplied to the fractionator of the system and the resulting reflux condensate is subjected in a heating coil to an outlet conversion temperature of approximately 950° F. at a superatmospheric pressure of about 350 pounds per square inch. Substantially the same pressure is maintained in the succeeding reaction chamber and the resulting vaporous and liquid conversion products are supplied to a separate vaporizing chamber maintained at a superatmospheric pressure of about 50 pounds per square inch. Vaporous products from this zone are supplied to the first mentioned vaporizing chamber while the high-boiling non-vaporous oils from both vaporizing chambers are supplied to a separate heating coil wherein they are quickly heated to an outlet temperature of approximately 980° F. at a superatmospheric pressure of about 30 pounds per square inch and the

highly heated heavy oils are introduced into alternately operated coking chambers maintained at substantially the same pressure. The pressure employed in the coking chamber is substantially equalized in the succeeding vaporizing chamber and in the fractionating, condensing and collecting portions of the system. This operation will produce, per barrel of charging stock, approximately 55 per cent of motor fuel having an octane number of approximately 70 by the motor method and approximately 120 pounds of low volatile coke of uniform quality and good structural strength, the remainder being chargeable, principally, to uncondensable gas.

I claim as my invention:

1. In a process for the conversion of hydrocarbon oils wherein oil recovered from within the system is subjected to conversion conditions of cracking temperature and substantial superatmospheric pressure in a heating coil, the resulting vaporous and liquid conversion products separated and the latter subjected to appreciable further vaporization in a reduced pressure vaporizing chamber, the remaining non-vaporous residual liquid heated to a relatively high temperature under non-coking conditions in a separate heating coil and then introduced into a coking chamber wherein its reduction to substantial dry coke is accomplished, the improvement which comprises imparting to said residual liquid in the separate coil sufficient heat to effect its reduction to coke in the coking chamber, withdrawing vaporous products from the coking chamber and contacting the same in a separate vaporizing chamber with relatively cool hydrocarbon oil charging stock for the process, whereby the charging stock is subjected to appreciable vaporization and undesirable high-boiling components are removed from the vaporous products, subjecting the remaining vapors to fractionation together with vaporous products from the first-mentioned vaporizing chamber whereby their insufficiently converted components are condensed as reflux condensate, supplying reflux condensate recovered by said fractionation to the first mentioned heating coil for said conversion, subjecting fractionated vapors of the desired end-boiling point to condensation, collecting the resulting distillate, withdrawing from the last mentioned vaporizing chamber high-boiling components of the charging stock remaining unvaporized in this zone, together with said high-boiling materials removed from the vaporous products supplied to this zone, and supplying the same to said reaction chamber wherein they are subjected to relatively mild conversion by contact with the highly heated products from the first mentioned heating coil.
2. In a process for the conversion of hydrocarbon oils wherein oil recovered from within the system is subjected to conversion conditions of cracking temperature and substantial superatmospheric pressure in a heating coil and communicating reaction chamber, the resulting vaporous and liquid conversion products separated and the latter subjected to appreciable further vaporization in a reduced pressure vaporizing chamber, the remaining non-vaporous residual liquid heated to a high temperature under non-coking conditions in a separate heating coil and the highly heated residual oil introduced into a coking chamber wherein its reduction to substantially dry coke is accomplished, the improvement which comprises imparting to said residual liquid in the separate coil sufficient heat to effect its reduction to coke in the coking chamber, withdrawing vaporous products from the coking chamber and contacting the same in a separate vaporizing chamber with relatively cool hydrocarbon oil charging stock for the process, whereby the charging stock is subjected to appreciable vaporization and undesirable high-boiling components are removed from the vaporous products, supplying liquid products of the contacting step from said separate vaporizing chamber to said separate coil, fractionating the uncondensed vapors from said separate vaporizing chamber and vaporous products from the first-mentioned chamber and supplying resultant reflux condensate to the first-mentioned coil, and finally condensing and collecting the fractionated vapors.

chamber and commingling the same, in a separate vaporizing chamber, with relatively cool hydrocarbon oil charging stock for the process whereby the charging stock is subjected to appreciable vaporization and undesirable high-boiling components are removed from the vaporous products, subjecting the remaining vapors to fractionation together with vaporous products from the first-mentioned vaporizing chamber whereby their insufficiently converted components are condensed as reflux condensate, supplying reflux condensate recovered by said fractionation to the first mentioned heating coil for said conversion, subjecting fractionated vapors of the desired end-boiling point to condensation, collecting the resulting distillate, withdrawing from the last mentioned vaporizing chamber high-boiling components of the charging stock remaining unvaporized in this zone, together with said high-boiling materials removed from the vaporous products supplied to this zone, and supplying the same to said reaction chamber wherein they are subjected to relatively mild conversion by contact with the highly heated products from the first mentioned heating coil.

3. A process as claimed in claim 1 wherein vaporous products from the first mentioned vaporizing chamber are supplied to said separate vaporizing chamber.

4. A process as claimed in claim 2 wherein vaporous products from the first mentioned vaporizing chamber are supplied to said separate vaporizing chamber.

5. In a process for the conversion of hydrocarbon oils wherein oil recovered from within the system is subjected to conversion conditions of cracking temperature and substantial superatmospheric pressure in a heating coil, the resulting vaporous and liquid conversion products separated and the latter subjected to appreciable further vaporization in a reduced pressure vaporizing chamber, the remaining non-vaporous residual liquid heated to a relatively high temperature under non-coking conditions in a separate heating coil and then introduced into a coking chamber wherein its reduction to substantially dry coke is accomplished, the improvement which comprises imparting to said residual liquid in the separate coil sufficient heat to effect its reduction to coke in the coking chamber, withdrawing vaporous products from the coking chamber and contacting the same in a separate vaporizing chamber with relatively cool hydrocarbon oil charging stock for the process, whereby the charging stock is subjected to appreciable vaporization and undesirable high-boiling components are removed from the vaporous products, supplying liquid products of the contacting step from said separate vaporizing chamber to said separate coil, fractionating the uncondensed vapors from said separate vaporizing chamber and vaporous products from the first-mentioned chamber and supplying resultant reflux condensate to the first-mentioned coil, and finally condensing and collecting the fractionated vapors.

CHARLES H. ANGELL.
